CLAIM

The ornamental design for an electric vehicle toy, as shown and described.

DESCRIPTION

FIG. 1 is a front, left, top perspective view of an electric vehicle toy, showing the first embodiment of my new design; FIG. 2 is a rear, right, top perspective view thereof; FIG. 3 is a front, right, top perspective view thereof; FIG. 4 is a front elevational view thereof; FIG. 5 is a rear elevational view thereof; FIG. 6 is a left side view thereof; FIG. 7 is a right side view thereof; FIG. 8 is a top plan view thereof; FIG. 9 is a front, left, top perspective view of an electric vehicle toy, showing the second embodiment of my new design; FIG. 10 is a rear, right, top perspective view thereof; FIG. 11 is a front, right, top perspective view thereof; FIG. 12 is a front elevational view thereof; FIG. 13 is a rear elevational view thereof; FIG. 14 is a left side view thereof; FIG. 15 is a right side view thereof; and, FIG. 16 is a top plan view thereof.

The evenly spaced broken lines shown in the drawings depict portions of the electric vehicle toy that form no part of the claimed design.
